UNITED STATES PATENT OFFICE

JOHN WEINEGEL, OF TAMPA SHORES, FLORIDA, ASSIGNOR, BY MESNE ASSIGNMENTS, TO PERFECT E. Z. CHAIR CORPORATION, OF NEW YORK, N. Y., A CORPORATION OF DELAWARE

COLLAPSIBLE RECLINING CHAIR

Application filed March 31, 1928. Serial No. 266,121.

This invention relates to chairs of the reclining and collapsible type; and the object of the invention is to provide a chair of the class described, constructed in the simplest, 5 possible manner to reduce the production costs to a minimum which will permit of the marketing of a chair having the features stated, at a selling price well within the reach of the population at large; a further object 10 being to provide a chair comprising a back rest, and a seat pivoted to the lower end of the back rest and a supporting frame or body in which the back rest and seat are pivotally mounted to freely move relatively to each 15 other and to said supporting frame to change the angular relation of the back rest and seat in the several reclining positions thereof which are automatically adjusted by the operator or party using the chair; a still further 20 object being to provide a supporting frame comprising crossed and oppositely disposed leg members, the upper ends of which are coupled together by arm members in connection with which the upper ends of the leg members 25 are pivotally coupled, means being provided for jointing the leg members where they intersect when the chair is in position for use, all of said parts being coupled to permit the collapsing thereof into a compact package in 30 a simple, effective and easily operable manner; a further object being to provide in conjunction with the forward end portion of the seat of the chair, a foot rest composed of a plurality of movably coupled parts with 35 means for supporting the same in spaced relation to the floor or other surface; and with these and other objects in view, the invention consists in a chair of the class and for the purpose specified, which is simple in construction, 40 efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a side view of the chair with the 50 several parts thereof in extended position.

Fig. 2 is a back view of the chair collapsed; and,

Fig. 3 is a side view of the chair in its collapsed position as seen in Fig. 2 of the drawing.

My improved chair comprises a seat member 5, back rest 6, side arms 7 and pairs of leg members 8 and 9, the leg members 8 being pivoted to the front ends of the arms 7, whereas the leg members 9 are pivoted to the rear ends of said arms. Pivoted to the forward end of the seat 5 is a foot and leg rest 10 consisting of separate parts 10^a, 10^b and 10^c, the part 10^a being pivoted to the seat, the part 10^b pivoted to the part 10^a as at 11 to prevent the downward collapsing of the parts 10^a—10^b and the part 10^c is in the form of a 60 rod for spacing and supporting the parts 10^a and 10^b with relation to the floor or other surface. The part 10^c is foldable inwardly 70 upon the part 10^b but when extended as seen in Fig. 1, supports the parts 10^a and 10^b against collapsing, and the part 10^c carries at its lower end a roller or other anti-frictional member 12, permitting of free movement 75 over the floor surface.

The seat 5 is pivoted to the lower end of the backrest 6 as seen at 13, and the forward end of the seat is pivotally supported in connection with the front ends of the arms 7 by 80 link rods 14, permitting of the free swinging of the seat forwardly and backwardly with respect to the arms 7 in the reclining of the chair and also in the operation of collapsing the several parts of the chair. The backrest 85 6 at a point above the pivot 13 and below the central portion thereof is pivoted to the rear ends of the arms 7 as seen at 15, so that in the normal position of the chair, the seat 5 will be inclined forwardly and upwardly and the 90 backrest 6 inclined to a slight degree with reference to the perpendicular plane as clearly seen in Fig. 1 of the drawing, so that when a party sitting in the chair desires to recline, 95 by simply leaning backwards, applying the weight of the body to the upper end portion 6^a of the backrest, the same will move backwardly, which operation will advance the seat 5 forwardly and upwardly. This operation may continue until all of the parts, 100

namely the seat 5, backrest 6 and leg or foot rest 10 are in substantially a common plane. It will be understood that the several parts of the chair may be maintained in different 5 automatic positions of adjustment to suit the comforts of the occupant of the chair by simply distributing the weight of the body on the respective parts, and without applying any undue tension or body pressure on the respective chair parts.

10 The leg members 8 and 9 are coupled together by providing a cross bar 16 substantially centrally of the leg members 8 and 15 sockets 17 on the under faces of the leg members 9 centrally thereof to receive the cross bar 16. Spring clips 18 are employed in conjunction with the sockets 17 to guide the rod 16 thereinto and to prevent accidental displacement of the rod in moving the chair about from place to place when in its position 20 for use. The lower ends of the arms 8 and 9 are braced by cross bars or rods 19 and 20 respectively and employed in conjunction with the rod 20 and the leg members 9 in a reinforcing arc-shaped member 21.

25 The lower face of the seat 5 adjacent the pivot end 13 is provided with a cross plate 22 to which is secured a rotatable catch device 23 adapted to engage the foot and leg 30 supporting member 10 when in collapsed position to retain the same against displacement. It will be noted from a consideration 35 of Fig. 2 of the drawing that the part 10^a of the member 10 where it is pivoted to the forward end of the seat 5 is narrower than the remainder of said part forming recesses 24 at the opposite sides of said narrower portion to permit of the convenient placement 40 of the feet upon the floor surface if the user of the chair should not desire to use the foot or leg rest, and also to facilitate convenience in the operation of sitting in the chair or getting up therefrom.

45 The operation of collapsing the chair from the position shown in Fig. 1 to the position shown in Figs. 2 and 3 is accomplished by moving the part 10^c onto the lower face of the part 10^b and said parts 10^a and 10^b swung on the pivot 11 onto the lower face of the part 50 10^a, and all of said parts thus collapsed, folded onto the under face of the seat 5 and secured in position by the catch device 23. The seat and backrest are now brought into substantially horizontal position or in common 55 alinement and the leg members 8 and 9 are uncoupled and the leg member 9 swung with its lower end to the front portion of the chair and the leg members 8 to the rear end of the chair and upon the under faces of the arms 7 60 forming the compact body seen in Figs. 2 and 3. In setting up the chair from a collapsed position, the above operation is reversed, the leg members being first coupled together, slight pressure applied to the pivotal connection of the seat and backrest at 13, swinging

65 said parts into the position shown in Fig. 1, after which the leg and footrest member 10 and its several parts may be extended. It will also be apparent that from the collapsed position of the chair, a large number of the 70 same may be stacked or stored in a comparatively small space and may be conveniently packed or crated for shipment, and in no case, is it essential to detach or uncouple bolts, screws, nails or like devices constituting 75 part of the chair structure.

80 My improved chair may have many uses and may be constructed in numerous different ways to suit the particular use thereof, some of which may be identified as steamer chairs, beach chairs, porch chairs, lounging chairs, camp chairs and the like, it being understood that the seat, backrest as well as the leg and foot rest may include canvas bodies or may be constructed of upholstered bodies in a more expensive chair structure in accordance with the present standards of 85 chair construction, and various other changes in and modifications of the structure herein shown and described may be made within the scope of the appended claims, without departing from the spirit of my invention or sacrificing its advantages.

90 Having fully described my invention, what I claim as new and desire to secure by Letters Patent, is:—

95 1. A collapsible reclining chair comprising spaced pairs of crossed pivoted supporting legs, arm rests supported by and pivotally connected with the upper ends of said legs, an inclined back rest pivotally supported between the adjacent ends of said arm rests, a seat pivotally connected with the lower edge 100 of the back rest and normally inclined upwardly therfrom, links depending from the forward ends of said arm rests and providing a pivotal connection between the latter and the forward end of the seat, whereby the seat and back rest is permitted to swing freely 105 between the arm rests to provide the desired reclining position, and means detachably connecting the supporting legs at their points of intersection, whereby said legs when detached can be moved in opposite directions and folded parallel with said arm rests, and the back rest folded in end to end relation with the seat.

110 2. A collapsible reclining chair comprising spaced pairs of crossed pivoted supporting legs, arm rests supported by and pivotally connected with the upper ends of said legs, an inclined back rest pivotally supported between the adjacent ends of said arm rests, a seat pivotally connected with the lower edge 115 of the back rest and normally inclined upwardly therfrom, links depending from the forward ends of said arm rests and providing a pivotal connection between the latter and the forward end of the seat, whereby the seat and back rest is permitted to swing freely 120 between the arm rests to provide the desired reclining position, and means detachably connecting the supporting legs at their points of intersection, whereby said legs when detached can be moved in opposite directions and folded parallel with said arm rests, and the back rest folded in end to end relation with the seat.

125 3. In setting up the chair from a collapsed position, the above operation is reversed, the leg members being first coupled together, slight pressure applied to the pivotal connection of the seat and backrest at 13, swinging

swing freely between the arm rests to provide the reclining position desired by the user of the chair, the pivot for said legs being carried by corresponding legs of each of the respective pairs, and a clamp carried by the other leg of each pair for detachable engagement with said pivot, whereby the legs of each pair can be separated and folded parallel with the arm rests, and the back rest arranged in end to end relation with the seat.

10 In testimony that I claim the foregoing as my invention, I have signed my name, this 26th day of March, 1928.

JOHN WEINEGEL.
